GRINDING APPARATUS

Alfred E. Hamilton, Pittsburgh, Pa.

Application January 18, 1943, Serial No. 472,696

10 Claims. (Cl. 51—40)

My invention relates to apparatus for the surfacing of materials of various kinds, such as strips or sheets of steel, transparent plastic sheets, etc., by grinding and polishing.

One object of my invention is to provide grinding and polishing apparatus comprising surfacing rolls and an improved mechanism for supporting them and moving them into and out of engagement with the materials to be surfaced.

Another object is to provide an improved arrangement of work-feeding apparatus in conjunction with surfacing rolls.

Another object of my invention is to provide an improved manner for initially shaping surfacing rolls to accurate cylindrical contour and to thereafter grind them, as occasion may arise.

Still another object of my invention is to provide an improved arrangement of splash guards for rolls that are mounted for swinging movement to and from operative position.

A further object is to provide an improved arrangement of surfacing roll elements and an improved means for assembling them in detachably connected relation.

Figure 1 is a side view of apparatus embodying my invention; Fig. 2 is a rear end view thereof, looking in the direction of the arrows II—II of Fig. 1; Fig. 3 is a plan view of a portion of the apparatus of Figs. 1 and 2; Fig. 4 is a perspective view schematically showing the arrangement of certain of the parts of the apparatus, including means for adjusting the surfacing rolls; Fig. 5 is an end view of a portion of the apparatus of Fig. 4; Fig. 6 is an end view of the feed rolls at the entrance end of the machine shown in Fig. 1, with certain parts added thereto; Fig. 7 is a sectional plan view of the structure of Fig. 6; Fig. 8 is an enlarged view of a portion of the structure of Fig. 1, showing the manner in which the water-spray shields of Fig. 1 are mounted with respect to the surfacing rolls; Fig. 9 is a rear face view of the shields of Fig. 8; Fig. 10 is an end view of one of the surfacing rolls or drums of Fig. 1, on an enlarged scale, showing the manner in which the abrasive strips are detachably held in the surfacing rolls; Fig. 11 is a view looking in the direction of the arrows XI—XI of Fig. 10; Fig. 12 is a view taken on the line XII—XII of Fig. 10; Fig. 13 is an inverted plan view of a portion of the structure of Fig. 10; Fig. 14 is a projected view showing one of the abrasive strips that are wound on the drum; Fig. 15 is a face view of one of the drums showing the abrasive strip helically wound thereon; Fig. 16 is an enlarged sectional view through a portion of one of the surfacing drums,

showing the manner in which an abrasive strip is wound thereon, and Fig. 17 is a fragmentary view, partly in longitudinal section, showing the manner in which air is supplied to the surfacing rolls and maintained therein at a desired pressure.

The apparatus is adapted for the surfacing of sheets or strips indicated by the numeral 2, and comprising a stationary base or foundation 3 that fixedly supports upstanding frame members 4 and 5 at the rear or delivery side of the machine and an intermediate frame member 6 that serves as a slideway for a reciprocable base member 7 that carries surfacing rolls 8 and 9 that are journaled in arms 10 and 11 respectively, that are supported by rods 12 and 13, on upstanding bracket members 15 (Fig. 2) which are mounted on the slidable base member 7.

The uprights 4 and 5 at the rear end of the machine (Fig. 1) have arms 17 formed thereon that serve as supports for bearing housings 18 and 19 for pairs of pinch rollers 20—21 and 22—23 respectively, that are employed in feeding the sheets 2 through the machine.

The base member 7 carries bracket members 24 that support cross-beams 25 and 26 upon which are adjustably supported bases 27 and 28 for motors 29 and 30 respectively. Threaded adjusting rods or screws 32 are rotatably supported in the beams 25—26, and have threaded engagement 30 with lugs 33 projecting downwardly from the bases 27 and 28, this adjustment being provided for shifting the motors, to tension the belt drives, to be hereinafter explained.

At the front end of the machine (Figs. 1 and 6) a slideway 35 is secured to the stationary base 3, for supporting a slide member 36. This member 36 has depending lugs 37 through which an adjusting screw 38 extends and has threaded engagement. The screw 38 is journaled on the slideway 35 and is provided with a hand wheel 39 by which it may be rotated to shift the slide 36 forwardly and rearwardly with respect to the surfacing rolls 8—9. The member 36 has upstanding bracket elements 41 at its ends that carry guides 42 and 43 for pairs of pinch rollers 44—45 and 46—47 that are employed to advance the sheets to the surfacing rolls 8—9.

The bearings for the lower feed rolls 45 and 57 are normally fixed in their brackets 42 and 43 respectively, but the bearings for the upper rolls 44 and 46 are vertically movable in their guides 42 and 43 and are yieldably urged downwardly by springs 48 and 49 respectively at each end. These springs at their upper end have engagement with blocks 50 and 51 respectively which have thrust

engagement with adjusting screws 52 and 53 respectively, that have threaded engagement with the guides 42-43, so that when the screws are turned in one direction, the spring-seating blocks 50 and 51 will be forced downwardly to compress the springs and thus cause the upper rolls 44-46 to bear more tightly on the sheets 2 or on the lower rolls 45-47.

The tension on the pinch rolls 20 and 22 heretofore referred to, is adjusted in like manner, by 10 their tensioning screws 55 and 56 that correspond to the screws 52 and 53.

The slideable base 7 is oscillated or reciprocated transversely of the path of the sheets 2 to effect reciprocations of the surfacing rolls 8 and 9, and this may be effected in the same manner as the surfacing rolls of my Patent 2,269,197 are reciprocated and vibrated, in order to effect more uniform surfacing of the strips or sheets passing through the machine. Since this feature does not per se constitute a part of the present invention, no detailed description thereof is required. However, in the present instance, a lever 58 (Fig. 2) is pivotally supported in the framework of the machine and at its upper end has a link connection at 59 with the reciprocable slide 7 that carries the surfacing rolls 8-9, so that as the lever is oscillated on its shaft 60, the slide member and the surfacing rolls will be reciprocated transversely of the path of travel of the sheets. A link 61 (Fig. 2) that functions as an eccentric rod is connected to the lower end of the lever 58 and has eccentric connection at 62 with a driving wheel or disc 63 which is driven from a motor 64, through a Reeves drive 64a, a driving belt 65, bevel gearing at 66 and worm gearing at 66a. As the eccentric disc 63 rotates, the link 61 will be reciprocated and thus effect reciprocations of the surfacing rolls as heretofore explained, together with the motors 29 and 30 which are carried by the base 7. This reciprocation will extend over a range of only a few inches.

The motor 64 is mounted on a base 67 that at 35 is pivotally supported upon a bracket 69. An adjusting screw 71 is rotatably supported by the bracket 69 and has threaded engagement with the base 67 of the motor, to raise and lower it, so that as the screw is rotated, the Reeves drive will be varied to change the speed of the disc 63.

The motor 29 through a belt drive 73 drives a pulley 74 that is secured to the shaft which carries the roll 9, while the motor 30, through a belt drive 75 drives a pulley 76 that is secured to the shaft that carries the surfacing roll 8.

The roll-supporting arms 10 that are pivotally supported upon the rod 12 and the roll-supporting arms 11 that are pivotally supported by the rod 13 are respectively adjustable about the axes of said rods for the purpose of varying the pressure which they exert upon the sheets to be surfaced, and to adjust the roll pass to sheets of various thicknesses. To this end links 78 are connected to the inner ends of the arms 10 and links 79 to the inner ends of the arms 11. Levers 81 are connected to the pairs of links 78-79 and these levers are rigidly secured to a shaft 82 that is carried by upstanding brackets on the slideable base 7.

A worm gear 84 is secured to the shaft 82 and is rotatably adjusted by a worm 85 that is journaled in a housing 86 which is secured to a disc-like or wheel member 87 that is loosely supported on the shaft 82 but has latched engagement at 88 with a bracket-like extension 89 on the slide 7. For ordinary adjustments of surfacing tension 70

or for variation in roll pass spacing, the worm 85 will be rotated by its hand-wheel 90 to effect shifting of the links 78 and 79 to rock the arms 10 and 11, thus moving the rolls 8-9 closer together or farther apart as the case may be. Where quick separation of the surfacing rolls is required, the latch at 88 may be tripped and the wheel 87 swung, thereby rotating the worm gear 84 more quickly than it could be turned through rotation of the worm 85.

The pinch rolls or feed rolls heretofore referred to are driven (Figs. 1 and 2) by a motor 91 through a belt 92, the motor being mounted upon a shiftable base 93, which is adjusted by a hand screw 94 to change the reduction rate of the Reeves pulley 91a. The belt 92, through a pulley 95 and suitable reduction gearing in a gear case 96 drives a sprocket chain 97 that passes around a sprocket wheel 98 (Fig. 3) on the shaft 99 which carries the pinch roll 21. The upper pinch roll 20 that cooperates with the roll 21 is idlingly driven through its contact with the lower pinch roll or with the sheets. The shaft 99 also carries a sprocket wheel 101 around which a chain 102 passes for transmission of driving force to a sprocket wheel 103 that is mounted on a shaft 104, that carries the lower pinch roll 23. The shaft 104 carries a second sprocket 105 for a drive chain 106 that drives a sprocket wheel 107 on a shaft 108 that carries the lower pinch roll 47. A second sprocket wheel 109 on the shaft 108 drives a sprocket chain 110 that passes around a sprocket wheel 111 on the shaft which carries the remaining lower pinch roll 45. The four lower pinch rolls 21, 23, 47 and 45 are therefore all driven from the motor 91.

By providing adjustment for the base member 36 that supports the pinch rolls at the entrance end of the machine, they can be shifted to a position close to the surfacing rolls, so as to properly feed sheets into the roll pass, and can be withdrawn from the rolls a sufficient distance so as not to constitute an obstruction to easy access to the rolls for the purpose of changing them or 40 for applying fresh abrasive material to the rolls, as hereinafter explained.

In Fig. 5 I show a means for preventing chattering of the surfacing rolls or drums 8 and 9, while surfacing a sheet or strip. To this end, nuts 114 that have swivel mounting on the arms 11 at each side of the machine have threaded engagement with screws 115 that extend loosely through guides 116 that have swivel mounting on the arms 10. The screws 115 each carries a nut 117 that serves as a seat for a spring 118. The upper end of the spring seats against the guide 116, so that when the rolls 8 and 9 are swung toward one another through operation of the worm gearing 84-85, the springs 118 will be compressed, thus providing tension that will prevent vibration or chattering of the rolls 8-9 during a surfacing operation. The tension of the springs can be adjusted by turning the screws 115 in the nuts 114, or by adjusting their nuts 117.

Referring now to Figs. 6 and 7, I show means whereby the rolls or drums 8 and 9 can be ground or surfaced to true cylindrical form, particularly where pneumatic drums of rubber or the like are employed, it being understood, however, that the apparatus could be employed in truing up solid surfacing drums. It is difficult to make rubber drums of exactly cylindrical contour, owing to the elastic or yieldable nature of the material. Again, after a drum has been in use for some time, certain portions thereof may stretch slight-

ly or it may become somewhat out of round through other causes. The apparatus of Figs. 6 and 7 serves as a convenient means for either truing the drums when first installed in the machine, or for restoring them to cylindrical contour after they have been in use.

A bracket member 120 is secured to the front of the stand for the feed rolls 44 to 47, this bracket member having a dove-tail formed thereon to slidably support a block or carrier 121 that carries a bracket 122 in which an abrasive roll 123 is journaled. A screw 124 is journaled in the bracket 120 and has threaded engagement with the carrier 121, so that when the screw 124 is turned, the roll 123 will be shifted along the faces of the rolls 8 and 9. The bracket 122 is slidable in vertical guideways in the carrier 121 and has threaded engagement with a screw 125 that is journaled in the carrier 121, so that when the screw 125 is turned, the abrasive roll 123 will be raised and lowered, to surface the roll 8 or the roll 9. The abrasive roll 123 can be frictionally held in its bearings, so that it will not rotate freely when in contact with the surfacing rolls and will, therefore, grind away protuberant areas on the surfacing rolls, or it could be rotated in a suitable manner counter to the direction of the rotation of the surfacing rolls. During such a grinding operation, the screw 124 will be operated to move the roll 123 along the faces of the surfacing rolls. The slidable mounting of the feed roll support 41 permits it to be moved away from the surfacing rolls far enough to allow convenient placing and removing of the grinding roll bracket 120.

In Figs. 8 and 9, I show the manner in which spray shield members 127—128 and 129—130 are mounted. These spray shields are for the purpose of confining loose grit and water spray, the spray being applied adjacent to the grinding zone, to prevent overheating of the surfacing rolls. The spray shield section 127 has arms 131 welded or riveted thereto, and these are secured to the roll-supporting arms 10 by bolts or screws, at 132. The shield section 127 also has arms 133 secured thereto, which are bolted or screwed to the lower side of the arms 10. Similarly, the shield section 129 is provided with arms 134 and 135 that are secured to the upper and lower sides respectively of the arms 11.

An angle bar 136 is disposed beneath the rock shaft 12 that carries the roll-supporting arms 10, and at each end carries arms 137 and 138. At their outer ends, the arms 137 are connected to the shield section 128 by bolts 139 that extend through the end wall of the shield and have threaded engagement with nuts 140 that are welded to the inner sides of the shield end walls. Similarly, the outer ends of the arms 138 are connected to the lower portion of the shield 128 by bolts or screws 141. When these bolts 139 and 141 are removed, the shield section 128 may be taken off, or it can be tilted back into the shield section 127.

An angle bar 142 is placed above the rock shaft 13 which carries the roll-supporting arms 11, and such bar 142 carries arms 143 at its ends, which through the use of bolts or screws 144 has detachable connection with the shield section 130. Arms 145 that are carried by the angle bar 142 have detachable connection at 146 with the shield section 129. In this case, removal of the screws or bolts 144 will permit the shield section 130 to be removed or to be swung back into the shield section 129.

The shield sections 127 and 129 have inturned flanges at 147 and 148 respectively, to form a groove into which the inner edges of the shield sections 128 and 130 respectively extend. The shield section 127 has lugs 150 welded thereto in position to rest on the shaft 12 and thereby support the shield section against sagging.

A scraper or deflector element 152 is pivotally supported between the arms 138 and is angularly disposed crosswise of the sheet 2, below a deflector plate 151 for the water and grit, to serve as a scraper or deflector bar, and thus deflect from the sheet 2 the grit and water that are carried to the forward part of the shield by the surfacing roll 8. Detritus is thus prevented from entering the surfacing roll pass. A spring 153 yieldably holds the scraper bar 152 against the sheet.

The shield section 129 has a trough-like portion 154 to receive detritus from the lower surfacing roll 9, the shield being open at one end of the trough 153 for convenient disposal of the detritus.

Spray pipes 155 and 156 are positioned along-side the shafts 12 and 13 and have water spray openings discharging through holes 157 and 158 in the shield sections 127 and 129 respectively, to direct water against the rolls and the sheet, at the roll pass.

Clips 160 carried by the bars 136 and 142 are firmly held against the shafts 12 and 13. When such shafts are turned during rocking of the arms 10 and 11 in opposite directions to separate the rolls, the upper and lower shields will also be moved away from one another. Guide bars 161 are secured to the arms 138 and 143 by screws, to prevent the strips or sheets being bulged or buckled between the surfacing rolls and the pinch rolls 22—23, as explained in my application Serial No. 461,121, filed Oct. 7, 1942.

In Figs. 10 to 16 I show details of one of the surfacing rolls of the other figures, it being usual to have both the upper and lower rolls of the same form. A roll shaft 162 has rigidly mounted thereon a metal hub 163 that carries a pneumatic drum 164 of rubber or other suitable material, air pressure being supplied to the annular space 165 within the drum, through a pipe 166, as hereinafter explained. An abrasive strip 167 is helically wound upon the drum 164. This strip may be of waterproof sandpaper, emery cloth or the like. The ends of the strip 167 are tapered as at 168, so that the end turns thereof will overlie a flange 169 that is formed on the hub, without projecting beyond the flange. The turns of the strip have an overlapping area at 171, and the outer wall of the drum 164 is helically grooved or depressed to accommodate the double thickness of strip at 171, thereby providing for a substantially smooth and continuous abrading surface.

The ends of the strip 167 are detachably secured to the annular flanges 169 at the ends of the hubs by metal straps or hoops 172. The tapered ends 168 of the strips are wrapped around the flanges 169 and the straps 172 placed over the same. The flange 169 is broken and has in-turned ends at 173 between which a portion of the strap is passed and extends around the shaft 162 and through a yoke 174. A pin 175 extends through the legs of the yoke for supporting an eye bolt 176 that extends loosely through a bracket member 177 which is screwed to the end of the hub 163. Nuts 178 are provided on the bolt 176, so that the yokes 174 can be drawn to-

ward the bracket members 177 to tighten the straps 172 on the ends of the abrasive strips and thus maintain the abrasive strips firmly in place during surfacing operations. An extension arm 179 carried by the bracket 177 surrounds the shaft 162 and serves as a brace to resist radial thrusts on the bracket member 177, when the nuts are turned to tighten the strap 172. Clip-like elements 181 are welded to the edge of the strap 172 and are provided with elongated holes 182 through which screws 183 extend, the inner ends of the screws being threaded into the flange 169. The screws 183, together with the clips 181, hold the strap against sliding off the flange 169, while the elongated holes allow the necessary slight circumferential movement or sliding of the strap 172 during the tightening thereof.

Referring now to Fig. 17, I show a manner in which air pressure is maintained within the drums 164 so that they will have sufficiently snug fit with their hubs to maintain them against turning on the hubs under grinding friction, and to maintain the helically-wound abrasive strips taut thereon. Also, the pressure can be controllably varied to suit various grinding conditions. For example, a high pressure will be employed when an intense surfacing action is required on a strip or sheet, and lower pressures for lighter grinding or surfacing operations. The pressure in the rolls may suitably vary from 5 lbs. to 20 lbs. per square inch, depending upon the grain size or nature of the working being operated upon.

The roll shafts 162 and 162a each has a passageway formed therein that communicates with one of the pipes 166, the said pipes, of course, rotating with the shafts. On the shaft 162, stuffing boxes 185 are mounted to seal a header sleeve 186 in which the shaft rotates. A hose or pipe 187 communicates through the sleeve 186 with the passageway in the shaft 162. A swivel joint 188 is provided at one end of the shaft 162a so that air flow can be maintained to the passageway in said shaft from a pipe 189, while the shaft is rotating.

A reservoir 190 is supplied with air under pressure through a pipe 191, from a suitable compressor (not shown). When it is desired that the pressures in the rolls be identical, air is supplied from the reservoir 190 past a pressure-reducing valve 192 and through a pipe 193 to the upper drum, while such supply will be through a pipe 194 to the lower drum. If pressures of different degrees are required in the upper and lower drums, a valve 195 in the line 194 will be closed, and a valve 196 in a line 197 will be opened. Thereupon pressure to the lower drum will be through a pressure-reducing valve 198 and through pipes 197 and 189, to the lower shaft 162a.

The pressure-reducing valves may be of any conventional form and can be adjusted by their handles 198 and 199, to automatically effect supply of air at a desired pressure to the drums, which pressure will ordinarily be somewhat less than the pressure in the reservoir 190. In order to prevent an excess of pressure being developed in the drums, as a result of heat through grinding friction or increase of atmospheric temperatures, I provide pressure relief valves 201 and 202 that are adjustable to permit exhaust of air from the drums at pressures above that at which the air is being supplied past the regulator valves 192 and 198. These valves 201-202 may be of conventional form and adjustments are made

therein by turning their adjusting screws 203 and 204 respectively.

This matter of the regulation of pressures in the drum is also important in order that the helically-wound abrasive strips 167 will be maintained in proper position upon the drums. Some strips will be wider than other strips that may be used on the drums and will, therefore, be wound on a different helical pitch than narrower strips. Again, some strips will have greater stretch under the expansive force of the air than other strips, and this stretching tendency will vary with the helical pitch at which a strip is wound on the drum. The pneumatic pressure must, of course, be sufficient to prevent displacement of the strip on the drum during grinding operation and must, nevertheless, not be so great as to rupture the strip. Reinforcing cords of fabric 205 are preferably provided in the rubber drums to control the expansion thereof and to assist in maintaining the cylindrical contour of the drum.

I claim as my invention:

1. Grinding apparatus comprising a pair of surfacing rolls positioned to engage opposite faces of a sheet, pivotally mounted arms supporting the rolls, a rock shaft, link connections between the said arms and the rock shaft, so arranged that upon oscillation of the shaft the rolls will be moved toward and away from one another, a spring yieldably resisting movement of the rolls toward one another, and means movable to oscillate the rock shaft, and serving to maintain the rock shaft at any position to which it has been turned, the said means comprising a worm and worm gear.

2. Grinding apparatus comprising a pair of surfacing rolls positioned to engage opposite faces of a sheet, pivotally mounted arms supporting the rolls, a rock shaft, link connections between the said arms and the rock shaft, so arranged that upon oscillation of the shaft the rolls will be moved toward and away from one another, means movable to oscillate the rock shaft, and means for tensioning the said arms against vibratory movements when they are in position to hold the rolls against a sheet.

3. Grinding apparatus comprising a pair of surfacing rolls positioned to engage opposite faces of a sheet, pivotally mounted arms supporting the rolls, a rock shaft, link connections between the said arms and the rock shaft, so arranged that upon oscillation of the shaft the rolls will be moved toward and away from one another, means movable to oscillate the rock shaft, and a spring in position to be stressed by said arms when they are moved toward one another to bring the rolls into engagement with a sheet.

4. Grinding apparatus comprising a pair of surfacing rolls positioned to engage opposite faces of a sheet, pivotally mounted arms supporting the rolls, a rock shaft, link connections between the said arms and the rock shaft, so arranged that upon oscillation of the shaft the rolls will be moved toward and away from one another, means movable to oscillate the rock shaft, splash shields carried by said arms and movable therewith, and means for introducing a water spray into the said shields and against the rolls.

5. Grinding apparatus comprising a pair of surfacing rolls positioned to engage opposite faces of a sheet, arms pivotally supported intermediate their ends and carrying the rolls at their outer ends, a rock shaft having crank arms extending in opposite directions, a link connection between

each crank and the inner end of one of the first-named arms, whereby rotative movement of the rock shaft in one direction will bring the rolls toward one another for engagement with a sheet, and rotative movement of the shaft in the opposite direction will effect separation of the rolls, and a spring yieldably resisting movement of the rolls toward one another.

6. Grinding apparatus comprising a pair of upper and lower surfacing rolls positioned to engage opposite faces of a sheet, a pair of pivotally mounted arms supporting one roll at its ends, a pair of pivotally mounted arms supporting the other roll at its ends, a rock shaft having crank arms extending in opposite directions, the crank arms that extend in one direction being connected with the supporting arms of the one roll and other crank arms being connected to the supporting arms of the other roll, means for rocking the said shaft to move the rolls toward and from one another, and a spring interposed between the roll arms at each end of the rolls, for yieldably resisting movement of the arms toward one another.

7. Grinding apparatus comprising a pair of upper and lower surfacing rolls positioned to engage opposite faces of a sheet, a pair of pivotally mounted arms supporting one roll at its ends, a pair of pivotally mounted arms supporting the other roll at its ends, a rock shaft having crank arms extending in opposite directions, the crank arms that extend in one direction being connected with the supporting arms of the one roll and other crank arms being connected to the supporting arms of the other roll, a worm gear mechanism for oscillating the rock shaft, to move the rolls toward and from one another, and a spring interposed between the roll arms at each end of the rolls, for yieldably resisting movement of the arms toward one another.

8. Grinding apparatus comprising a pair of surfacing rolls positioned to engage opposite faces

of a sheet, pivotally mounted arms supporting the rolls, a rock shaft, link connections between the said arms and the rock shaft, so arranged that upon oscillation of the shaft the rolls will be moved toward and away from one another, a spring yieldably resisting movement of the rolls toward one another, means movable to oscillate the rock shaft and serving to maintain the rock shaft at any position to which it has been turned, the said means comprising a worm and worm gear, and a latch device for releasably retaining the worm gear in position to hold the rolls in cooperative relation with a work piece, whereby upon tripping of the latch, the rolls will automatically be moved to inoperative positions, under the influence of the said spring.

9. Grinding apparatus comprising a pair of surfacing rolls positioned to engage opposite faces of a sheet, pivotally mounted arms supporting the rolls, a rock shaft, link connections between the said arms and the rock shaft, so arranged that upon oscillation of the shaft the rolls will be moved toward and away from one another, means movable to oscillate the rock shaft and serving to maintain the rock shaft at any position to which it has been turned, a spring arranged to yieldably resist movement of the rolls into work-engaging position, and a latch device for releasably holding the rock shaft in position at which the rolls will engage a work piece, whereby upon tripping of the latch, the spring will move the rolls to inoperative position.

10. Grinding apparatus comprising a surfacing roll mounted for engagement with a work piece, means for moving the roll toward and from its operative position, a spring arranged to resist movement of the roll to its operative position, and a latch for retaining the roll in its operative position, whereby upon release of the latch, the roll will be moved by said spring to inoperative position.

ALFRED E. HAMILTON.
